(57) **CLAIM**

The ornamental design for an attachment for cosmetic skin treatment apparatus, as shown and described.

DESCRIPTION

FIG. 1 is a perspective view of an attachment for cosmetic skin treatment apparatus;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom view thereof.

The portions of the attachment for cosmetic skin treatment apparatus shown in broken lines form no part of the claimed design.
